(57) CLAIM

The ornamental design for a shatranj/chess set as shown and described.

DESCRIPTION

FIG. 1 is a left side plan view of the shatranj/chess set, showing my new design;

FIG. 2 is a front plan view thereof;

FIG. 3 is a top plan view thereof;

FIG. 4 is a bottom plan view thereof;

FIG. 5 is a back plan view thereof;

FIG. 6 is a top, front, right side perspective view thereof;

FIG. 7 is a top, front, left side perspective view thereof;

FIG. 8 is a top, back, left side perspective view thereof;

FIG. 9 is a front plan view of the Shah or King piece of the shatranj/chess set, shown separately for ease of illustration;

FIG. 10 is a bottom plan view thereof;

FIG. 11 is a top plan view thereof;

FIG. 12 is a front plan view of the Vizier or Queen piece of the shatranj/chess set, wherein the back and side views are mirror images thereof, shown separately for ease of illustration;

FIG. 13 is a bottom view thereof;

FIG. 14 is a top view thereof;

FIG. 15 is a left side plan view of the Elephant or Bishop piece of the shatranj/chess set, shown separately for ease of illustration;

FIG. 16 is a front view thereof;

FIG. 17 is the back view thereof;

FIG. 18 is a top plan view thereof;

FIG. 19 is a bottom plan view thereof;

FIG. 20 is a left side plan view of the Horse or Knight piece of the shatranj/chess set, wherein the right side view is a mirror image thereof, shown separately for ease of illustration;

FIG. 21 is a front plan view thereof;

FIG. 22 is a back plan view thereof;

FIG. 23 is a top plan view thereof;

FIG. 24 is a bottom plan view thereof;

FIG. 25 is a front plan view of the Rook piece of the shatranj/chess set, wherein the back and side views are mirror images thereof, shown separately for ease of illustration;

FIG. 26 is a top plan view thereof;

FIG. 27 is a bottom plan view thereof;

FIG. 28 is a front plan view of the Pawn piece of the shatranj/chess set, wherein the back and side views are mirror images thereof, shown separately for ease of illustration;

FIG. 29 is a top plan view thereof; and,

FIG. 30 is a bottom plan view thereof.
